BATTEN CONSTRUCTION FOR NARROW FABRIC LOOMS

Application filed October 3, 1928. Serial No. 310,042.

This invention relates to battens for use in narrow fabric looms for the production of ribbon, tape, and other similar fabrics. In such looms, there is a multiplicity of shuttles 5 mounted in raceways defined by guide blocks disposed on the batten, and these shuttles are reciprocated in the raceways in unison by suitable mechanism. More particularly, the present invention is concerned with the provision of a batten of novel sectional construction with respect to the shuttle guide blocks and their mountings, the sectional parts of the batten being capable of ready removal and replacement, so that new sections with 10 blocks of different lengths and with spacings of different widths between the raceways may be placed on the batten when the loom is to be changed from the production of a fabric of one width to another.

In narrow fabric looms, the batten is usually constructed to carry shuttles in upper and lower rows adapted to pass through sheds, the reeds for which are placed in staggered relation in two rows. Each shuttle 20 has a pair of raceways, one on each side of the reed past which the shuttle moves, and the raceways and shuttles are of uniform construction, so that each raceway may be occupied by one shuttle at the start of shuttle 25 movement in one direction and by the next adjacent shuttle in the row at the completion of the shuttle movement in that direction.

The length of the shuttles employed and the length of the raceways depends on the 30 width of the fabric being woven, within certain limits. A shuttle of a given length may be used economically with ribbons of a given width, and as the ribbon width increases, longer shuttles are necessary, so that these 40 shuttles may span the reed and engage at each end in a raceway at each side of the reed while passing through the shed. The guide blocks defining these raceways must have a length corresponding to the length of the 45 shuttles which are to move in them. As a consequence, when the loom is changed from the production of a fabric of one width to that of another, it is necessary to replace the shuttles and guide blocks on the batten with others of a size appropriate for the fabric to 50

be made. In the ordinary batten, as now used, such a change consumes a great deal of time during which the loom is out of operation and it is the practice to carry two or more battens in stock for each loom, these battens being adapted for the production of fabrics of different widths, and when a change is made, the entire batten is removed from the loom and a new one substituted. As battens 55 represent a considerable item of expense, it follows that the necessity of keeping several battens on hand for each loom greatly increases the overhead cost of production, and the necessity of changing battens from time 60 to time reduces the productivity of the loom and adds to the cost of the product.

The object of the present invention is to provide a batten of sectional construction which includes shuttle guide blocks and 70 mountings constructed in suitable units, which can be readily removed from the batten and replaced with others of a different kind when a production change is necessary. These batten sections are of simple, inexpensive 75 construction and are capable of being mounted in the batten without delicate adjustment, so that the change can be effected quickly with the loom out of operation only a short time.

Preferably, these sections are made up of 80 frame members which are mounted on the batten beam and, if desired, may extend between that beam and the upper rail, although I contemplate the use of sections, each of 85 which includes a member which serves as a part of the upper rail. On these frame members are disposed pairs of guide blocks forming the raceways in upper and lower rows, and disposed in staggered partially overlapping 90 relation. Each section may provide simply a pair of raceways in upper and lower rows defined by upper and lower pairs of blocks, or each section may include more raceways. Mounted on each section is at least one reed and more are employed if the section includes more than a pair of raceways. These sections are attached to the beam and to the upper rail, if such a rail is 95 present, in any suitable manner by readily operable connections and when the batten is 100

to be changed as required by the change from one fabric to another, all of the sections are removed and others of appropriate construction substituted for them. This change is readily accomplished by the mounting means provided.

For a better understanding of the invention, reference will be made to the accompanying drawings, in which,

10 Fig. 1 is a fragmentary view in front elevation of a portion of a batten constructed in accordance with the present invention;

15 Fig. 2 is a sectional view on the line 2—2 of Fig. 1;

15 Fig. 3 is a front view of one of the sections;

Fig. 4 is a rear view of one of the sections;

20 Fig. 5 is a fragmentary front view of a part of the batten showing a modified form of the section;

Fig. 6 is a sectional view on the line 6—6 of Fig. 5;

25 Fig. 7 is a sectional view on the line 7—7 of Fig. 5; and

25 Fig. 8 is a fragmentary rear view of the section as illustrated in Fig. 5.

Referring now to these drawings, the batten 10 is illustrated as consisting of a beam 11, and an upper rail 12 connected by suitable cross-frame members 13. This batten is mounted for swinging movement on supports, not shown, and in the operation of the loom is swung forward and backward in the direction at right angles to its plane.

35 Mounted on the batten in upper and lower rows are shuttles 14, these shuttles being movable in raceways defined by guide blocks 15. Each shuttle passes through a shed formed by warp threads which pass through a reed 16 and there is a raceway for each shuttle on each side of each reed.

The shuttles illustrated are reciprocated by an actuator bar 17 carrying plates 18 adapted to be received in slots 19, formed in the ends of the shuttles. This bar 17 is mounted in any suitable way between the shuttles of the upper and lower rows and at one end is attached to an upright arm 20 on a slide 21 connected by spaced rods 22 to an upper 23. These slides 21 and 23 are movable as a unit in guideways provided in the beam and the upper rail respectively, and the slides are reciprocated by means of a lever 24 carrying a pin 25, which enters the space between the rods 22. As the lever is swung, the slides 21 and 23 are reciprocated lengthwise of the batten and in their movement cause an endwise movement of the actuator bar 17. This bar is provided at one end with a pin 26 entering a slot 27 in a tubular cam 28, which causes the bar to be rocked through 180° at appropriate intervals in its movement.

35 The actuator bar and the mechanism by which it is driven form no part of the pres-

ent invention, but are illustrated and described in my co-pending application Ser. No. 208,918, filed July 28, 1927. It is sufficient to say that at the beginning of the shuttle movement in one direction, each shuttle is engaged by a plate 18 on the bar entering a slot 19 on the trailing end of the shuttle and when the leading end of the shuttle has passed through the shed, the bar is rocked a half-turn and the plates are carried out of engagement with the trailing ends of the shuttles of one row and into engagement with the leading ends of the shuttles of the other. Each plate then engages and carries that shuttle with the bar to the end of the shuttle movement. On the return, the sequence of operations is reversed.

One type of batten section constructed in accordance with the present invention is illustrated in Fig. 3 and this section consists of a pair of frame members 29 in the form of straps adapted to extend between the beam and upper rail. Mounted across the straps are blocks 15a which together define a shuttle raceway for a shuttle in the lower row, and mounted on one of the straps are guide blocks 15b defining a raceway for a shuttle of the upper row. These raceways are illustrated in staggered relation and partially overlap, the blocks 15b being attached at one end to one of the strap members 29. Mounted in the space between the strap members is a reed 16 which may be attached to the upper guide block 15a and to a suitable cross-piece 30 at its upper end. This reed is detachable from the section.

The section is a complete unitary structure, preferably made integral, with the exception of the reed, and the straps and the guide blocks may be made of wood or metal. The guide blocks are channeled as indicated at 31 to receive flanges 32 on the base of the shuttles and these channels are smoothly finished to provide a suitable raceway for the shuttle. The complete section if of metal may be made as a single metal casting.

As a convenient means of mounting the sections on the batten, the beam may be provided with longitudinal ribs 31', and the strap members suitably channeled as indicated at 32', so as to permit the channels to receive the ribs. Preferably the ribs and channels form a dovetail connection. The upper rail is also provided with a lengthwise rib 33 and the frame members 29 channeled at 34 so that these channels may receive the rib. Each of the frame members 29 is also provided with threaded holes in which may be mounted bolts 35 which can be screwed into the holes to bear against the ribs 31' and 33 to hold the sections in proper position.

With this arrangement, when the batten is to be assembled for operation, the sections are slipped on the ribs and moved along approximately to the positions they are to oc-

cup. The first section is then placed in the desired position of adjustment and secured there by tightening the bolts 35. This section may be one like that illustrated in Fig. 3. Then the next section is moved along until the free end of the guide blocks 15b overlie the adjacent frame members 29 on that section and the ends of these blocks are then secured to that frame member by suitable fastening means which pass through openings 36 in the blocks and openings 37 in the frame member which are brought into registry therewith. The second section is then secured in position by tightening its bolts and the third section moved up. These operations are repeated until the entire group of sections has been placed in proper relative positions.

It will be seen that the operation of adjusting the sections in proper relation to each other is very simple, since each section determines the position of the section following it in the series, and the only adjustment that needs to be made accurately is the positioning of the first section, the others being simply moved along the batten until the openings in their strap members register with openings in the free ends of the blocks of the preceding sections. When a change in the fabric is necessary, the bolts holding the sections in position are loosened, the connections between the sections removed and all of the sections slipped off the ends of the rods.

The section illustrated in Figs. 3 and 4 is single in the respect that it carries a single raceway for shuttles in each of the rows. In some instances, it may be desirable to use a section of larger size, which includes more than the one raceway in each row. For this purpose, the construction illustrated in Figs. 5 to 8, inclusive, may be employed.

In the arrangement illustrated in those figures, the top rail of the batten is dispensed with and mounted on the rear face of the beam is a plate 38. Each batten section includes a pair of end frame members 39, which extend across the face of the plate 38 and have a recess or channel 40 in which the plate is snugly received. The engagement of the end walls of the channels with the side edges of the plate holds the section rigidly in upright position and adjacent sections are secured to the batten by means of strap members 41, each of which is attached to the beam by means of a bolt 42 threaded into an opening in the plate 38. Each strap member overlies an end frame member 39 of two adjacent sections and when the bolts are tightened, the sections are clamped to the rear face of the beam.

The upper ends of the end frame members 39 are connected by a frame member 43, which serves as a part of the upper rail with which these battens are usually provided. Also extending across the members 39 is a

lower frame member 44 resting on the upper edge of the plate 38 and partially overlying that plate. Connecting the members 43 and 44 between the end frame members 39, are straps 45. The spacing between the straps and the end frame members and between adjacent straps is uniform.

Attached to each end frame member 39, and also attached to the adjacent strap member 45, are guide blocks 46a, and these guide blocks are arranged in pairs to define raceways for a shuttle in the lower row. Connecting the strap members 45 are similar guide blocks 46b, which define a raceway for a shuttle in the upper row. Also mounted on each end frame member 39 projecting outwardly therefrom are half-blocks 47, each member 39 carrying a pair of these half-blocks, as illustrated.

With this arrangement, when the batten is to be assembled, the first section is placed in proper position and the next section is moved up against it until the ends of the two rail members 43 of the sections lie in contact. Then the sections are secured to the batten by means of the clamp plates 41. In this position the half-blocks on each section cooperate with those on the adjacent section to complete a raceway in the upper row, and as each section carries two parts of these half-blocks, when all of the sections are assembled on the batten, the necessary raceways for all of the shuttles in the upper and lower rows are provided.

The several parts of each section, as described, constitute a complete unitary structure and this structure if of metal may be made as a single metallic casting, the blocks being later machined to provide the necessary shuttle channels. Each section also carries the appropriate number of reeds (not shown) mounted thereon in any convenient manner, such for instance, as that illustrated in Fig. 3.

With either construction, the adjacent blocks forming parts of guideways in the upper and lower rows may also provide a raceway for a part of the shuttle actuating mechanism, and for this purpose each of the upper blocks such as 46a and each of the lower blocks such as 46b is provided at its ends with extensions, which cooperate to form a raceway 49. In this raceway may lie a slide 49' carrying brackets 49a in which the shuttle actuator bar 17 is mounted and this slide is connected to the upright arm 20 and moved thereby, the rocking bar 17 being movable endwise with the slides in the brackets and rocked at the appropriate instant by the cam 28. The slide in the raceway 49 is held in place by plates 50, which close the entrance to the raceway and are detachably secured in position by screws 51.

This batten construction affords certain advantages over that illustrated in Figs. 3

and 4 in that fewer sections of the modified type are required in a complete batten and any one section can be removed without affecting the others. It sometimes happens that a shuttle may be injured or broken and replacement of a batten section required. This does not happen frequently, but with the modified construction a single section with the injured shuttle can be readily removed, whereas with the construction shown in Figs. 3 and 4, all of the sections between that to be removed and one end of the batten would have to be taken off to permit the removal of the one injured.

In each of the section constructions illustrated, the section is a complete unitary structure which may be integral throughout, with the exception of the reeds, and these sections may be made of cast metal. As the sections are all of the same construction, the cost of their production is relatively low, since they are made from the same pattern. This sectional batten construction affords many important advantages above pointed out, since it avoids the necessity for keeping several battens in stock and as the sections required for any batten are relatively cheap, the investment in sections necessary for fabrics of different widths does not represent an item of any considerable importance in overhead. Furthermore, this investment is repaid many times in the course of use by reason of the saving in time required to change the loom from one fabric to another, since that change can be effected in a short time without removing the entire batten.

While I have shown the sections with one suitable arrangement of the guide blocks, it is evident that other arrangements may be employed without departing from the invention.

This application is a continuation in part of my co-pending application, Serial No. 211,885, filed August 10, 1927.

I claim:

A batten for a narrow fabric loom which comprises a beam, and a plurality of sections mounted on said beam side by side lengthwise of said beam, each section comprising a pair of spaced upright members removably attached to said beam, a pair of shuttle guide blocks mounted on said upright members and extending between them, a second pair of shuttle guide blocks mounted on one of said upright members and offset both laterally and longitudinally relative to the first pair of guide blocks, adjacent blocks of said pair defining an open mounting for an element for driving the shuttles and members connecting said adjacent guide blocks for closing said mounting.

In testimony whereof I affix my signature.
HERMAN BAADER.
